(57) **CLAIM**

An ornamental design for an anchor assembly sleeve, as shown and described.

DESCRIPTION

This application is related to the following commonly owned co-pending patent applications: U.S. application Ser. No. 16/243,541, entitled "Self-Drilling Anchor Assembly"; U.S. application Ser. No. 29/676,208, entitled "Anchor Assembly Drill Bit"; U.S. application Ser. No. 29/676,214, entitled "Anchor Assembly Drill Bit"; U.S. application Ser. No. 29/676,217, entitled "Anchor Assembly Drill Bit"; U.S. application Ser. No. 29/676,225, entitled "Anchor Assembly Drill Bit"; U.S. application Ser. No. 29/676,229, entitled "Anchor Assembly Drill Bit"; U.S. application Ser. No. 29/676,241, entitled "Anchor Assembly Sleeve"; and U.S. application Ser. No. 29/676,243, entitled "Anchor Assembly Sleeve".

FIG. 1 is a top perspective view of an anchor assembly sleeve of my new design.

FIG. 2 is a top view of the anchor assembly sleeve of FIG. 1, the bottom view being a mirror image thereof.

FIG. 3 is a first side view of the anchor assembly sleeve of FIG. 1, the opposite second side view being a mirror image thereof.

FIG. 4 is a front end view of the anchor assembly sleeve of FIG. 1; and,

FIG. 5 is a rear end view of the anchor assembly sleeve of FIG. 1.

The broken line showing of various surface features is included for the purpose of illustrating portions of the anchor assembly sleeve and forms no part of the claimed design.
